UNITED STATES PATENT OFFICE.

HIRAM J. WHITE, OF SPRINGFIELD, MASSACHUSETTS.

PEPPER-BOTTLE.

SPECIFICATION forming part of Letters Patent No. 249,562, dated November 15, 1881.

Application filed April 13, 1881. (No model.)

To all whom it may concern:

Be it known that I, HIRAM J. WHITE, of Springfield, in the county of Hampden and State of Massachusetts, have invented certain new and useful Improvements in Pepper-Bottles, of which the following is a specification.

The object of my invention is to provide a pepper-bottle with means of connecting the cover thereon in a simple, cheap, and convenient manner, as hereinafter more fully described and set forth; and it consists in the construction, combination, and arrangement of a spring-catch within the cover and an external groove around the neck of the bottle, near the mouth of the same, as hereinafter more fully described.

Figure 1 represents a perspective view of my invention. Fig. 2 represents a vertical central section of the same.

A represents a bottle, formed of glass or other suitable material, having an external groove, B, formed around the neck, near the mouth of the same; and P represents a perforated cover, formed of metal or other material, and having a vertical flange, E, adapted to fit over the neck of the bottle, and is provided at one side in its lower edge with a projection, C, formed internally or bent inwardly, so as to engage into the said groove B when the cap or cover is placed over the mouth of the bottle. This cap or cover is provided opposite the projection C with a spring-catch, D, and an internal curved

or semicircular spring, H, which rests within a slight groove formed circumferentially within the cap or cover, and has one end bent outwardly and projected through the vertical flange E thereof, and has a bearing against the inner face of the thumb-piece G of the said catch D, which is hinged or loosely connected with the said flange E by projections *tt*, which are passed through holes therein, and are bent over or in any suitable manner.

It will be seen that if the thumb-piece G be pressed upon inwardly the catch or hooked end D will be freed from the groove B by compressing the curved spring H, and when released therefrom the cap or cover may be raised at that side and removed from the bottle when required to cleanse or fill the same.

Having thus described my invention, what I claim is—

The combination, with the bottle A, having the groove B, of the perforated cover P, having the vertical flange E, provided with the projection C and the semicircular spring H, and pivoted thumb-piece G, having a catch, D, all being constructed and arranged substantially as shown and described, as and for the purposes set forth.

HIRAM J. WHITE.
